CONTOUR DUPLICATOR

Andrew J. Amato, Winchester, and Joseph R. L. Dudgeon, Arlington, Mass.

Application May 18, 1954, Serial No. 430,524

4 Claims. (Cl. 33—175)

This invention relates to gauge devices, and more particularly to an improved implement for use in obtaining an accurate outline of a contour to be matched, such as for obtaining an accurate outline of the contour of an irregular piece of molding or the like to which another piece is to be joined.

A main object of the invention is to provide a novel and improved contour duplicating device for obtaining an exact facsimile of an angle, curve, or other irregular contour on an object to be fitted or other structure to be matched, the device being simple in construction, being easy to manipulate and providing an accurate reproduction of the contour of the object against which it is placed.

A further object of the invention is to provide an improved contour duplicator which provides an accurate reproduction of a contour to be fitted and also provides a quantitative measurement both longitudinally and transversely of said contour, the device involving inexpensive components, being rugged in construction, and being easy to read.

Further objects and advantages of the invention will become apparent from the following description and claims, and from the accompanying drawings, wherein:

Figure 1 is a perspective view of an improved contour duplicating device constructed in accordance with the present invention.

Figure 2 is a side elevational view of the contour duplicating device of Figure 1.

Figure 3 is a top plan view of the sleeve-like housing of the contour duplicating device of Figures 1 and 2.

Figure 4 is an enlarged side elevational view of the rotary wedge member employed in the device of Figures 1 and 2.

Figure 5 is an end elevational view of the wedge member of Figure 4.

Figure 6 is a top view of the wedge member of Figure 4.

Figure 7 is a perspective view of the lamination guide collar employed in the device of Figures 1 and 2.

Figure 8 is a perspective view of one of the laminations employed in the contour duplicating device of Figures 1 and 2.

Figure 9 is an enlarged cross sectional detail view taken on the line 9—9 of Figure 10.

Figure 10 is a top plan view of the device of Figure 1, shown engaged with a molding whose contour is to be duplicated and illustrating the manner of using the contour duplicating device.

Referring to the drawings, the contour duplicating device is designated generally at 11 and comprises a generally rectangular sleeve-like housing 12 having the rectangular bottom wall 13, the relatively narrow side walls 14 and 15, and the transversely extending, relatively short top wall 16 which is located at the forward end of the housing 12. Designated at 17 are a plurality of identical laminations which are slidably disposed in the housing 12 for longitudinal sliding movement therein, the

2

laminations 17 being disposed in side-by-side relationship, as is clearly shown in Figures 1, 7 and 8, and having enlarged forward head portions 18 which project from the forward end of the housing member 12 adjacent the relatively short top wall 16 of the housing.

Surrounding the laminations 17 immediately adjacent the enlarged head portions 18 of the laminations is a rectangular collar member 19 having the same transverse cross sectional shape as the housing 12 and being provided with the transversely extending upstanding flange 20 arranged to abut the shoulders defined between the upper portions of the head elements 18 and the remainder of the laminations. The head elements 18 are also formed with the depending portions 21 having bottom edges coplanar with the bottom plane of housing 12.

The head elements 18 are formed with tapered ends 22 defining vertical abutment edges 23 at the forward tips of the head elements which are engageable against a contour to be duplicated, as will be presently described.

20 Designated at 24 is a wedge member which is generally triangular in shape and which is formed with an aperture 25 at one corner through which extends a transverse lug 26 defined between a pair of longitudinally extending slots 27 and 28 formed in the housing top wall 16 adjacent the side walls 15 thereof, as is shown in Figure 3. The wedge member 24 is formed at the corner thereof opposite the aperture 25 with the transversely extending finger lug 29 which normally engages the top surface of the wall 16 of housing 12, as shown in Figure 1. Wedge member 24 has a tapered intermediate portion 50. The tapered intermediate portion 50 of the wedge member 24 is interposed between the last lamination 17 and the side wall 15 of the housing, as is clearly shown in Figure 7. This frictionally locks the laminations against longitudinal movement. When the pivotal wedge member 24 is rotated counterclockwise from the position thereof shown in Figure 1, as by elevating the finger lug 29, the tapered intermediate portion 50 of the rotary wedge 24 is disengaged from between the laminations and the side wall 15, releasing the laminations for longitudinal sliding movement in the housing 12.

The top wall 16 is formed with a transversely extending inch scale 30 which is located at the transverse edge of the wall opposite the head elements 18 of the laminations, as shown in Figure 3. The top surface of the bottom wall 13 of the housing 12 is provided with a longitudinally extending depth scale 31 which may be calibrated in inches, similar to the calibrations of the scale 30, which is visible when the laminations are moved forwardly through the housing 12, as illustrated in Figure 8.

50 In using the device, the rotary wedge member 24 is moved to its released position, as by elevating the lug 29, leaving the laminations free for longitudinal sliding movement in the housing 12. The head elements 21 are then engaged against the contour to be measured, such as the molding contour 32 shown in Figure 8, the abutment portions 23 of the head elements being engaged against the contour 32 and the laminations being moved substantial distances through the housing 12, to expose the depth scale 31 on the top surface of bottom wall 13, as is shown in Figure 8. The forward portions of the laminations 17 are supported by the collar 19, the upstanding flange 20 on said collar serving to hold the head portions 18 of the laminations engaged with the straight portion of the molding 32 in alignment.

65 The laminations are provided at their rear ends with upstanding lug elements 33, whereby the laminations may be manually pushed into positions wherein their head tips 23 closely engage the contour to be duplicated, and said contour is then duplicated at the rear ends of the laminations, as is clearly shown in Figure 8. The laminations may then be locked by rotating the rotary wedge 28

to the position thereof shown in Figure 1, namely, to a position wherein the finger tab 29 engages the top wall 16, in which position the laminations 17 are frictionally secured in adjusted positions in housing 12.

The contour 32 will thus be duplicated at the rear ends of the laminations 17, namely, at the upstanding lugs 33, and the mating contour will be defined by the configuration of the abutment tips 23 at the forward ends of the laminations. The relative depth of the various portions of the contour may be read from the longitudinally extending scale 31 on the top surface of the bottom wall 13, and the transverse locations of the different points along the contour may be determined from the transversely extending scale 30 provided on the top wall 16.

While a specific embodiment of an improved contour duplicating device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A contour duplicating device comprising a sleeve-like housing member having a top wall, a plurality of identical laminations slidably disposed in said housing member in side-by-side relationship and projecting from said housing member, the ends of said laminations being adapted to be disposed against the contour to be duplicated, a wedge member pivoted to said housing member for rotation in a plane parallel to the planes of said laminations and being rotatable in said plane to wedgingly engage at least one of said laminations in said plane to exert wedging force normal to said plane and to frictionally lock said laminations in fixed positions in said housing member, and means on said wedge member engageable with said top wall when said wedge member has been rotated to a position frictionally locking said laminations in fixed positions.

2. A contour duplicating device comprising a sleeve-like housing member having a top wall, a plurality of identical laminations slidably disposed in said housing member in side-by-side relationship and projecting from said housing member, said laminations having tapered ends adapted to be disposed against a contour to be duplicated a wedge member pivoted to said housing member adjacent said tapered end for rotation in a plane parallel to the planes of said laminations and being rotatable in said plane to wedgingly engage at least one of said laminations to exert wedging force normal to said plane and to frictionally lock said laminations in fixed positions in said housing member, and means on said wedge member engageable with said top wall when said wedge member has been rotated to a position frictionally locking said laminations in fixed positions.

3. A contour duplicating device comprising a sleeve-like housing member having a top wall, a plurality of identical laminations slidably disposed in said housing member inside-by-side relationship and projecting from said housing member, said laminations having tapered ends adapted to be disposed against a contour to be duplicated, a wedge member pivoted to said housing member adjacent said tapered ends for rotation in a plane parallel to the planes of said laminations and being rotatable in said plane to wedgingly engage between one of the laminations and a side wall of said housing member to exert wedging force normal to said plane and to frictionally lock said laminations in fixed positions in said housing member, and means on said wedge member engageable with said top wall when said wedge member has been rotated to a position frictionally locking said laminations in fixed positions.

4. A contour duplicating device comprising a generally rectangular sleeve-like housing member having a top wall, a plurality of identical laminations slidably disposed in said housing member in side-by-side relationship and projecting from said housing member, said laminations having tapered ends adapted to be disposed against a contour to be duplicated, the top wall of said housing member being relatively short as compared with the remainder thereof and being located adjacent the tapered ends of the laminations, a wedge member pivoted to said top wall adjacent said tapered ends for rotation in a plane parallel to the planes of said laminations and being rotatable in said plane to wedgingly engage between one of the laminations and a side wall of said housing member to exert wedging force normal to said plane and to frictionally lock said laminations in fixed positions in said housing member, a transversely extending scale on said top wall, a longitudinally extending scale on the bottom wall of said housing member, and a laterally extending lug on the upper edge of said wedge member engageable with said top wall when said wedge member has been rotated to a position frictionally locking said laminations in said fixed positions.
